UNITED STATES PATENT OFFICE

ENRICO MINI, OF BROOKLYN, NEW YORK

WINDOW CONSTRUCTION

Application filed November 8, 1928. Serial No. 318,080.

This invention relates to improvements in window constructions and has particular reference to a sash mounting.

An object of the invention is to provide an improved mounting for sashes which will enable the same to be swung horizontally inward from the frame in which they are vertically slideable to enable them to be cleaned with safety, ease and facility.

10 The above and other objects will appear more clearly from the following detailed description, when taken in connection with the accompanying drawings, which illustrate a preferred embodiment of the inventive idea.

15 In the drawings—

Figure 1 is a front elevation of a window constructed in accordance with the invention;

Figure 2 is a fragmentary elevation, partly broken away and shown in section;

20 Figure 3 is a sectional view showing the manner of detachably securing the parting strips in position;

Figure 4 is a fragmentary perspective view of the window showing the lower sash swung 25 inward and the upper sash in a position to be similarly adjusted;

Figure 5 is a horizontal sectional view illustrating the sashes in their normal positions; and

30 Figure 6 is a similar view showing the sashes swung inwardly.

Referring more particularly to the accompanying drawings, the numeral 7 indicates generally the frame of a window to the vertical stiles of which are secured the parting strips 8 and the molding 9. The parting strips on the left-hand side of the window frame, as viewed in Figures 1 and 4, are rigidly secured to the frame, while those on the right-hand side, as shown in Figures 1 and 3, are detachably secured to the frame for the purpose of permitting the inward horizontal swinging of the sashes, as will later appear. Any suitable means may be provided for fastening the latter parting strips in position, an example of which is shown in Figures 1 and 3, wherein two or more plates 10 are countersunk in the window frame and each provided therein with a screw-threaded recess 11 adapted to receive the threaded end of a

screw 12, the shank of which extends through an opening 13 in the parting strip 8 with the head 14 of the screw engaging said strip to retain it in position. The upper and lower sashes 15 and 16 are supported for vertical 55 sliding movement in the window frame by suitable flexible elements, such as chains or ropes 17. In the particular embodiment shown in Figure 2, a channel or groove 18 extends downwardly from the top and along the outer edge of each vertical stile of a sash and at the lower end of said groove there is secured therein an eye screw 19 to which the lower hooked end of the chain 17 is attached. When a sash is swung inwardly the chain 17 60 at the right-hand side remote from the pivotal point of the sash is disengaged from its screw 19 and may be temporarily engaged with the hook 20 (Figure 1) secured to the side of the window frame. Thus, the chain 17 65 will not interfere with the full inward swinging movement of the sash.

For the purpose of hingedly connecting the sashes to the left-hand side of the window frame, each sash is provided with a pair of 70 hinges. The hinges 21 of the lower sash each have one of their leaves 22 secured to the molding 9 and, when the sash is in its normal position and free to slide vertically, the leaf 22 of each hinge is disconnected from the remainder of the hinge, as is the case also in connection with all of the hinges employed for both sashes. The remainder of each hinge 21 consists of two pivotally connected leaves 23 and 24, the latter of which is secured to the meeting rail of the lower sash and both of which are preferably countersunk in the surface of said rail when said leaves are in extended position, as shown in Figure 6. In the normal or inoperative position of each hinge, the leaf 23, which is disconnected from the leaf 22, may be swung back upon the leaf 24, as indicated at the left of Figure 1, so that the hinge will in nowise interfere with the vertical movement of the sash. However, when it is desired to swing the lower sash inwardly, each hinge is adjusted to the position shown in Figure 5, so that the leaf 23 will engage the leaf 22 and a pintle 25 is then employed to join said 100

leaves. The leaves 23 and 24 of each hinge are of such proportion that, when joined to the leaf 22, they will assume the position shown in Figure 5, in which they extend diagonally outward. This is done for the purpose of permitting a limited amount of movement of the sash 16 laterally outward from between the central parting strip 8 and the molding 9, during which the leaves 23 and 24 will become aligned, this movement being preparatory to swinging the sash horizontally inward and made possible for the purpose of allowing the outer corner of the sash to clear the central parting strip 8 when the sash is swung to the position shown in Figure 6. It will be understood, of course, that before the lateral movement of the sash relative to the vertical stile of the window frame is accomplished, the inner parting strip or molding on the right-hand side of the window frame must be detached by the removal of the screws 12 holding it in place and the chain 17 disconnected from the sash. A very slight inward swinging movement of the sash is sufficient to expose its vertical stile so that the chain 17 may be easily disconnected, and this slight movement also makes it possible to accomplish the lateral movement of the sash previously referred to, which is necessary to clear the left-hand vertical stile of the sash from the central parting strip. With the lower sash 16 in the adjusted position shown in Figure 6, it will be obvious that both sides of the glass of the sash may be thoroughly cleaned by a person standing in the room and, therefore, without danger of falling from the window.

The upper sash 15 is likewise provided with a pair of hinges 26 of the same construction as the hinges 21 and adapted to be detachably connected to the central parting strip 8 by pintles 27 when it is desired to swing the upper sash inwardly. Like the leaves 23 and 24 of the hinges 21, the corresponding leaves of the hinges 26 permit of a lateral movement of the sash 15 from between the central and outer parting strips 8. When it is desired to adjust the upper sash 15 to its open position, as shown in Figure 6, said sash is first lowered to the position shown in Figure 4, whereupon its hinges 26 are connected to the central parting strip 8 at the left of the window. The similar parting strip at the right-hand side of the window is then detached by removing the screws 12 and the same operation, as previously described in connection with the sash 16, is effected with the result that the upper sash may be adjusted, as in Figure 6, by swinging the same about its pivotal connections 28 with the hinges 26.

What is claimed is:

In a window construction, the combination with a window frame, and parting strips therefor; of a sash slidable in said frame and

engaging said strips, removable means to detachably secure one of said strips to one side of said frame, hinges connecting said sash to the other side of said frame, each hinge including a plurality of sections, one of which is secured to said frame and others to said sash, the latter sections being disposed at angles to one another when the sash is in sliding position between said strips and being movable to aligned position to permit a limited lateral movement of said sash away from the last-named side of said frame, and means detachably and pivotally connecting the first-named section of hinge with one of said other sections to permit of a horizontal swinging movement of said sash relative to said frame.

In testimony whereof I have affixed my signature.
